UNITED STATES PATENT OFFICE.

LIPA POLINKOWSKY, OF ANTWERP, BELGIUM, ASSIGNEE TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

Application filed September 10, 1919. Serial No. 322,943.

To all whom it may concern:

Be it known that I, LIPA POLINKOWSKY, a citizen of Russia, residing at 14 Rue du Bastion, Antwerp, Belgium, have invented 5 certain new and useful Improvements in Automatic Telephone-Exchange Systems, of which the following is a full, clear, concise, and exact description.

This invention relates to telephone systems and more particularly to systems in which automatic switching apparatus is employed for establishing talking connections between subscribers' lines.

The object of the invention is to provide 15 an arrangement whereby a talking connection may be established between subscribers' lines through the agency of a plurality of different types of automatic switching apparatus.

20 A feature of the invention consists in an arrangement of switching and controlling apparatus whereby a talking connection between two subscribers' lines may be established in part by automatic selective switches 25 of the power-driven type and in part by automatic selective switches of the step-by-step type.

A further feature relates to the provision; 30 in a system involving exchanges equipped with power-driven switches and exchanges equipped with step-by-step switches, with interconnecting trunks between such exchanges; of means operative when an inter-exchange call is made to control the step-by- 35 step switches in the called exchange for completing the desired connection.

A still further feature consists in the provision, in a system where the power-driven switches are arranged to be controlled by a 40 register sender controlling mechanism, of means adapted to cooperate with such mechanism for the purpose of operating step-by-step switches to complete the establishment of a desired connection.

45 Other features and advantages of the present invention will become apparent from a consideration of the following description and the appended claims.

In the accompanying drawings which 50 illustrate a telephone system embodying the novel features of this invention, Fig. 1 shows circuits and apparatus in a telephone exchange equipped with automatic switches of the power-driven type. To the left of 55 the broken line is shown a subscriber's line

incoming to the exchange and also a group selector switch adapted to extend such line in the establishment of connections. To the right of the broken line there is shown the outgoing end of a trunk circuit leading to a 60 distant exchange together with circuits and apparatus appertaining to said trunk circuit.

Fig. 2 shows an exchange provided with automatic switches of the step-by-step type, 65 the incoming end of said trunk circuit terminating in a step-by-step selector to the left of the broken line. To the right of the broken line is shown the detailed circuits of a step-by-step connector having access to 70 called subscribers' lines.

Fig. 3 shows a subscriber's line terminating in the exchange at an operator's position and also a switch, corresponding to the one shown in Fig. 1, by means of which the subscriber's line may be extended to the outgoing trunk. 75

According to this invention, a system is arranged in which subscribers to an exchange equipped with switches of the power- 80 driven or continuous movement type are enabled to obtain telephone connections with subscribers' lines terminating in distant exchanges provided with switching apparatus of the step-by-step type, as well as 85 with subscribers' lines local to their own exchange. As is the usual practice in power-drive systems, a calling subscriber, upon initiating a call, has his line automatically extended to a register controlling mechanism, in case of a full automatic system 90

which he thereupon proceeds to set up in accordance with the designation of the called line. In case of a semi-automatic system, the calling subscriber usually communicates the wanted number to an operator who, by means of the keyboard, registers the desired number on the controlling mechanism. The controlling mechanism 95

when thus positioned, operates automatically to control the selective operation of the switches to complete the extension of the calling line to the desired called line. In the system shown, subscribers to the exchange are given facilities apart from those above outlined, whereby connections may be extended to trunk lines leading to distant exchanges of the step-by-step type and there further extended over step-by-step selector switches to the line of a desired subscriber. 100

105

110

Whether the call is local or one to a distant step-by-step exchange, the register controlling mechanism is positioned either under the control of the subscriber's line directly or by means of an operator's keyboard. In the event of an inter-exchange call, the controlling mechanism after having controlled the operation of each selector switch to select an outgoing trunk line, continues in its operation in conjunction with apparatus associated with said trunk to cause the operation of the step-by-step switches in the distant exchange.

In the drawings, it has not been considered necessary to give more than a detailed showing of a power-driven group selector switch and a register controlling mechanism for controlling the operation thereof. This switch may be of any well-known construction in which a rotatable brush carriage is adapted to be driven from a continuously operating source of power to drive its brushes over the terminals of connecting circuits. The structure of such a switch is shown and described in patent to McBerty No. 1,097,868 of May 26, 1914. The register controlling mechanism is indicated briefly within the broken line in the lower left-hand corner of Fig. 1 and may comprise a plurality of sequence switch registers which, after having been adjusted from a calling subscriber's line or from an operator's keyboard, are restored to their normal positions by means of a stepping relay in the well-known fundamental circuit to perform the desired selective operation. Selective switches and a register controlling mechanism of the general character suitable for operation in the present system are shown and described in detail in the patent to Pollockowsky No. 1,365,269, issued January 11, 1921.

It is believed that a clearer understanding may be had of the present invention by describing in detail the establishment of a connection from one subscriber's line to another.

Assume that a subscriber to the line 100 in the power-driven exchange wishes to converse with the subscriber at line 200 terminating in a distant exchange equipped with step-by-step switches. When the subscriber at substation 100 removes his receiver from the switchhook, his line is extended in the well-known manner through to the repeating coil 103 over conductors 101, 102 either by means of automatic finder switches or by the agency of operators' connecting switches such as shown in Fig. 3. If the system is of the full automatic character, the calling subscriber may then position the register controlling mechanism, shown diagrammatically at 150, whereas if the system is of the semi-automatic type, the operator, by means of her keyboard adjusts the register controlling mechanism in accordance with the des-

ignation received from the calling subscriber. When the register mechanism has been positioned, brush selection takes place in a well-known manner at the group selector, one set of brushes of which is shown at 107, 108, 109. For this purpose, the brush tripping spindle magnet 117 is energized in a circuit including contact and armature of relay 114. Relay 114 may be energized in a circuit such as follows: Battery through the winding of said relay, contact 155 of a sequence switch individual to the group selector, through the winding of stepping relay 116, of the register mechanism, contact and armature of relay 115, contact 156 of the sequence switch belonging to the register controlling mechanism to ground at contact 113. Magnet 117 causes the power-driven shaft 147 to be applied to the tripping spindle in the well-known manner. After brush selection has taken place, the sequence switch of the group selector moves, as is well understood, to an advanced position as, for example, position 5. The relay 114 will become energized over a circuit including contacts 123 and 124. The brush carriage power magnet 125 is now energized and operatively associates the brush carriage with a continuously driven member 126. The circuit for the magnet 125 may be traced from battery through the winding of said magnet, back contact and armature of relay 119, contact 170, to ground at the contact and armature of relay 114. The brush carriage rotates to advance its brushes 107, 108, 109 over the terminals 110, 111, 112 of the selected level of trunks. In the case assumed, these trunk lines lead to the distant step-by-step exchange. When the test brush 109 reaches the test terminal 112 of an idle trunk, a selectable potential being found thereon, test relay 120 is energized over the following circuit: battery 127, contact 135 (1) of sequence switch 130 individual to the trunk circuit, terminal 112, brush 109 to ground through the left-hand high resistance winding of test relay 120. Relay 120 energizes and closes a low resistance path to ground through its right-hand winding and the winding of relay 119. The relay 119, by attracting its armature, opens the power circuit of magnet 125 bringing to rest the brushes 107, 108, 109 on terminals 110, 111, 112. The low resistance circuit to ground through relay 119 decreases the potential on the multiples of terminals 112 so as to render the selected trunk busy to other selector switches. In the well-known manner, the operation of relay 119 serves to drive the sequence switch (not shown) which controls the circuits of the group selector switch into an advanced position, such as position 6. The fundamental circuit is now extended from the register mechanism 150 to relay 121 at the outgoing end of the selected trunk

line. This circuit extends from battery through the winding of relay 121, contact 136 (1), terminal 111, brush 108, contact 106 (6) through the winding of stepping relay 116, contact and armature of relay 115, contact 156, contact 105 (6), brush 107, terminal 110 to ground at contact 137. Relays 121 and 116 energize the relay 121 closing a circuit from ground over its left-hand armature and front contact, contact 131 (1), through the winding of sequence switch 130 to battery. Sequence switch 130 moves out of position 1 and into position 2. During the time sequence switch 130 is passing from position 1 to position 2, its local contact 144 is closed to ground and relay 122 is energized in the following circuit: from the free pole of battery, contact 142, through the winding of relay 122, contact 141 to ground at local contact 144. Relay 122 is again de-energized as soon as the circuit just traced opens at contact 144 in position 2 of sequence switch 130.

When sequence switch 130 reaches position 2, the outgoing end of the trunk line 151, 152 is closed and stepping relay 201 of the first selector 230 becomes energized. The circuit for relay 201 is traceable from battery, through the right-hand winding thereof, back contact and inner left-hand armature of relay 228, conductor 151, conductor 153, contact 303 (1) of sequence switch 300, conductor 154, contact 143 (2) of sequence switch 130, conductor 152, outer left-hand armature and back contact of relay 228 through the left-hand winding of relay 201 to ground. Relay 201 attracts its armature and closes a circuit from ground, outer right-hand armature and contact of relay 228, armature and front contact of relay 201, through the winding of slow-to-release relay 202 to battery. Relay 202 operates and prepares a circuit for the second slow-to-release relay 203 and the primary stepping magnet 204. At the same time that sequence switch 130 reaches position 2, a circuit is closed from battery through the winding of sequence switch 300, contact 131 (2) to ground, at the front contact and left-hand armature of relay 121. The local contact 304 of sequence switch 300 is so arranged that said sequence switch is only permitted to stand at rest in position 1. When, therefore, sequence switch 300 is driven out of position 1, it runs through a complete cycle of operation. The contact 303 of sequence switch 300 is closed in positions 1, 2, 3, and so on up to position 10. The openings between these successive positions are so taken in connection with the speed at which sequence switch 300 is driven, that the trunk line, 151, 152 is intermittently opened and closed by the contact 303 in the same manner that it would be opened and closed under the control of a substation

transmitter. Furthermore, the contact 303 after having passed its tenth opening position and goes into position 11, it remains closed thereafter through to position 18. This comparatively long closed period of 70 contact 303 corresponds to the interval in which a calling subscriber at a substation is adjusting his dial for the transmission of the next series and is designed to permit ample time for the selective switch to complete its trunk hunting operation. When, therefore, sequence switch 300 passes out of position 1, contact 303 opens the circuit of stepping relay 201 at the first step-by-step selector 230. Relay 201 retracting its armature, closes a circuit from ground, outer right-hand armature and back contact of relay 228, armature and back contact of relay 201, inner armature and front contact of relay 202 through the windings of relay 203 and magnet 204 to battery and ground. The primary stepping magnet 204 energizes in the well-known manner and steps the brushes 208, 209, 210 into operative relation with the first level of trunk terminals. The slow-to-release relay 203 also energizes in this circuit. When sequence switch contact 303 reaches position 2, the trunk 151, 152 is closed and relay 201 opens the circuit of magnet 204 which deenergizes 90 preparatory to advancing the brushes of the selector switch another step. The contact 302 of sequence switch 300, also closed in position 2, completes the following alternate circuit for relay 121: battery, through the winding of relay 121, contact 302 (2), contact 139 (2), back contact and armature of relay 122, contact 140 (2) to ground. Relay 121 remains energized but the circuit just traced shunts out the stepping relay 100 116 at the controlling mechanism 150. In the manner well understood, the release of relay 116 prepares for the advance through another step of a controlling register upon which the hundreds designation of the called 105 line is registered. When sequence switch 300 leaves position 2, the trunk circuit 151, 152 is opened a second time, relay 201 deenergizes and the primary stepping magnet 204 operates to advance the selector brushes 208, 110 209, 210 opposite the next level of trunks. Between positions 2 and 3 of sequence switch 300, contact 302 opens to remove the shunt from around the stepping relay 116 in the fundamental circuit. Relay 116 energizes and a controlling register of the mechanism 150 advances another step. In position 3 of sequence switch 300, contact 303 closes to again cause the deenergization of stepping magnet 204 and contact 302 short-circuits stepping relay 116 causing this relay to deenergize. This operation continues until the controlling register of the mechanism 150 reaches its normal position at which time relay 115 energizes in a well- 115 120 125 130

known manner to open the fundamental circuit. As soon after this occurrence as contact 302 of sequence switch 300 is again opened, the relay 121 deenergizes. The retraction of the left-hand armature of relay 121 closes a circuit including contact 132 (2) to drive the sequence switch 130 out of position 2 and into position 3. The sequence switch contact 303 has thus opened and closed the trunk circuit 151, 152 a number of times corresponding to the setting of the controlling mechanism 150 and primary stepping magnet 204 has advanced the brushes 208, 209 and 210 to the proper level of trunks leading to connector switches such as 240. Dependent upon the size of the digit, the sequence switch 300 will be in one of its positions between position 1 and position 11, at the time the fundamental circuit is opened and sequence switch 130 goes into position 3. If the digit be less than ten, sequence switch 300 will not have reached position 11. To insure that contact 303 cannot open the trunk circuit to falsely operate the stepping magnet 204 during the time sequence switch 300 is reaching position 11, the trunk circuit is maintained closed by a substitute circuit and stepping relay 201 is held energized. This circuit for relay 201 may be traced from battery through the right-hand winding thereof, back contact and inner left-hand armature of relay 228, conductors 151 and 153, contact 133 (3), right-hand armature and back contact of relay 121, conductor 154, contact 143 (3) conductor 152, outer left-hand armature, and back contact of relay 228 through the left-hand winding of relay 201 to ground. The sequence switch 300 continues to run through the remainder of its cycle under the control of local contact 304.

On the first primary step of the selector switch 230, the primary off-normal contacts 229 and 231 are closed. Relay 206 energizes in a circuit from battery through the winding of said relay, contact 229, front contact and armature of relay 203 to ground at the front contact and outer armature of relay 202. When relay 201 attracts its armature permanently after the completion of the primary movement, slow-to-release relay 203 deenergizes after the elapse of an interval of time. The deenergization of relay 203 closes a circuit from battery, through the winding of the secondary stepping magnet 205, right-hand armature and contact of relay 206, back contact and armature of relay 203 to ground at the contact and outer armature of relay 202. The release of the armature of relay 203 opens at the same time the circuit traced for relay 206, but relay 206 does not release its armatures until after the stepping magnet 205 has had time to operate. While the initial operating circuit of relay 206 is opened upon the release of relay 203,

a substitute circuit exists for relay 206 as follows: battery, through the winding of said relay, off normal contact 229, left contact of magnet 205, winding of relay 228 to ground at the contact and outer armature of relay 202. The resistance of relay 228 is comparatively high, such that the relay 206 cannot operate when placed in series with relay 228, as will be seen hereinafter. Moreover, the relay 206, if operated, and then included in series with relay 228, cannot maintain its armatures attracted. In the latter case, however, the relay 206, although normally a quick operating relay, releases gradually since the relay 228 permits a certain amount of current to flow. Hence, while the relay 206 is holding its armatures attracted for an interval following the release of relay 203, the above traced circuit is completed for the secondary stepping magnet 205. The magnet 205 operates and advances the brushes 208, 209, 210 on to the first set of terminals in the selected level of trunks. Relay 206 now releases its armatures and opens the energizing circuit of stepping magnet 205. If the first trunk leads to a connector switch which is busy, ground will be found on the test terminal 213 thereof and relay 206 becomes energized in a circuit from battery, through the winding of said relay, contact 229, contact and outer armature of stepping magnet 205, back contact and inner armature of relay 228, test brush 210, terminal 213 to ground at the front contact and left-hand armature of relay 215. Relay 206, by attracting its armature, closes an operating circuit of stepping magnet 205 and brushes 208, 209 and 210 are advanced through a second step. The operation of the stepping magnet 205 now opens the circuit of relay 206 which deenergizes and by releasing its right-hand armature opens the circuit of magnet 205 causing said magnet to also deenergize. This method of operation proceeds until the test brush 210 reaches an ungrounded terminal 213. Relay 206 then remains deenergized and the brushes 208, 209 and 210 are brought to rest with terminals 211, 212 and 213 of a trunk leading to an idle connector switch 240. During the trunk hunting operation and while test brush 210 is continually in engagement with grounded terminal 213, the circuit from battery through relay 206, contact 229 and contact and outer armature of magnet 205 leads directly to ground over the back contact and inner right-hand armature of relay 228 and test brush 210. As soon as an idle trunk is found, however, upon the terminal 213 of which no ground exists, the circuit through relay 206 may be traced to ground in the following manner: battery through the winding of relay 206, contact 229, contact and outer armature of magnet 205 through the winding of relay 228

to ground at the contact and outer armature of relay 202. Relay 228, being no longer short-circuited by a circuit to ground over test brush 210 becomes energized. The relay 228 and relay 206 are so adjusted that relay 228 will energize whereas relay 206 does not energize in series with relay 228.

Relay 228 opens the circuit of stepping relay 201 and extends the trunk conductors 151, 152 through to the connector switch 240. Stepping relay 214 now energizes in a circuit from battery through the left-hand winding thereof, terminal 211, brush 208, front contact and inner left-hand armature of relay 228, conductors 151 and 153 to conductor 154 either over sequence switch contact 303 or sequence switch contact 133 and the right-hand armature and back contact of relay 121 thence returning by contact 143, conductor 152, outer left-hand armature of relay 128, brush 209, terminal 212 through the right-hand winding of relay 214, side switch arm 222 (position 1) to ground. Relay 214 closes a circuit over its armature and front contact for the energization of slow-to-release relay 215. The relay 215, at its left-hand armature and front contact, places a busy ground upon the multiples of terminals 213 to render the connector switch 240 non-selectable to other selector switches. At the time the relay 201 released its armature, it opened the circuit for relay 202 which, in turn, opened the original energizing circuit of relay 228. The relay 202, however, being sluggish in releasing, does not sever the circuit of relay 228 until after the slow-to-release relay 215 at the connector switch is energized. Therefore, the relay 228 is maintained operated in a circuit from battery through the winding of relay 206, contact 229, contact and outer armature of magnet 205 through the winding of relay 228, front contact and inner armature of relay 228, brush 210, terminal 213 to ground at the front contact and left-hand armature of relay 215. Relay 215 also prepares a stepping circuit for the primary magnet 217 in series with a second slow-to-release relay 216.

When sequence switch 300 reaches its normal position 1, sequence switch 130 is driven from position 3 into position 4 by means of a circuit including contact 132 (3) and contact 301 (1) of sequence switch 300. The apparatus is now in condition to control the primary selecting operation of the connector switch 240. The fundamental circuit is again closed and relays 121, 116 are both energized. Relay 121 closes a circuit from battery through the winding of sequence switch 300, contact 131 (4) to ground at the front contact and left-hand armature of relay 121. Sequence switch 300 thereupon leaves position 1 and under the control of its local contact 304 runs through a com-

plete cycle of operation. When contact 303 leaves position 1, the trunk 151, 152 is opened and stepping relay 214 is energized. Relay 214 closes a circuit from battery, side switch arm 221 (position 1) through the 70 windings of primary stepping magnet 217 and relay 216, contact and right-hand armature of relay 215 to ground at the back contact and armature of relay 214. The primary stepping magnet 217 operates in the 75 well-known manner to advance the brushes 232, 233 and 234 of the connector switch into operative relation with the first level of line terminals. The slow-to-release relay 216 also energizes and closes a circuit for the 80 escape magnet 219. In position 2 of sequence switch 300, contact 303 closes the trunk circuit 151, 152, relay 214 energizes and stepping magnet 217 deenergizes. Contact 302 in position 2 of sequence switch 300 85 short-circuits the stepping relay 116 above described and the tens register at the controlling mechanism 150 is prepared to advance through another position. On leaving position 2, sequence switch 300 once 90 more opens the trunk circuit 151, 152, relay 214 deenergizes and the stepping magnet 217 operates a second time to advance brushes 232, 233 and 234 into operative relation with the second level of line terminals. Relays 215 and 216 being slow to release maintain their armatures attracted during the interruptions of the trunk circuit. After the register controlling mechanism 150 is operated in accordance with the 100 registration of the tens digit, relay 115 opens the fundamental circuit and upon the next opening of contact 202, relay 121 is deenergized. Relay 121 closes a circuit including 105 its left-hand armature and back contact and contact 132 to drive sequence switch 130 into position 5. The trunk circuit 151, 152 is again closed at the right-hand armature and back contact of relay 121 independent of contact 303 and maintains stepping relay 110 214 energized during the time the sequence switch 300 is running through its remaining positions to position 1. Relay 214 being energized for a sufficient period causes the deenergization of slow-to-release relay 216. 115 Relay 216 opens the circuit of the escape magnet 219 which deenergizes and releases the side switch into its second position.

Upon sequence switch 300 reaching its 120 position 1, a circuit is closed from battery through the winding of sequence switch 130, contact 132 (5) to ground at contacts 301. Sequence switch 130 moves into position 6. The fundamental circuit is closed again in the usual manner and relays 121 and 116 125 energize. Relay 121 closes a circuit from ground over its left-hand armature and front contact and contact 131 (6) to drive the sequence switch 300 out of position 1. Sequence switch 300 completes its final 130

cycle of operation under the control of its local contact 304. In the manner similar to that already described, the contact 303 causes the opening and closure of trunk 5 151, 152 to cause the operation of relay 214 in accordance with the units digit. At the first retraction of the armature of relay 214, a circuit is closed from ground, armature and back contact of said relay, right-hand 10 armature and contact of relay 215 through the winding of relay 216, contact and left-hand armature of relay 223 through the winding of the secondary stepping magnet 218, side switch arm 221 (position 2), to 15 battery and ground. The stepping magnet 218 operates to advance the brushes 232, 233 and 234 onto the first set of terminals in the selected level. Relay 216 energizes in the circuit traced and again closes an energizing 20 circuit for the escape magnet 219. For each succeeding retraction of the armature of relay 214, the brushes 232, 233 and 234 are advanced over one set of terminals and finally come to rest in contact with the 25 terminals of the called line. When the last impulse has been sent and relay 121 de-energizes, sequence switch 130 is driven into position 10 by means of a circuit including contact 132 (6) and the back contact and 30 left-hand armature of relay 121.

When sequence switch 130 passes through position $7\frac{1}{2}$, relay 121 is energized in a circuit from battery through the winding of said relay, contact 135, terminal 112, brush 35 109 to ground through the high resistance winding of relay 120. Relay 121 closes a locking circuit for itself including contact 134, front contact and right-hand armature of relay 121, contact 133 and resistance 40 128. The relay 120 does not energize in this circuit. In position 10 of sequence switch 130, a circuit is established from battery, through the lower right-hand winding of repeating coil 103, winding of supervisory 45 relay 104, contact 106, brush 108, terminal 111 to ground at contact 136. Supervisory relay 104 therefore becomes energized. As soon as sequence switch 130 reaches position 7, relay 122 energizes in 50 a circuit from battery through the left-hand winding of relay 214, terminal 211, brush 208, front contact and inner left-hand armature of relay 228, conductor 151, contact 142, through the winding of relay 55 122, contact 141, conductor 152, outer left-hand armature and front contact of relay 228, brush 209, terminal 212 through the right-hand winding of relay 214, side switch arm 222 (position 2) to ground. After the 60 last impulse of the units series has been sent, relay 214 holds its armature attracted for an interval of time sufficient to permit the de-energization of slow-to-release relay 216. If the called line 200 is idle, no ground po-

tential exists on test terminal 235 and when 65 relay 216 deenergizes, the escape magnet 219 releases the side switch into its third position. Relay 226 operates in a circuit from battery over side switch arm 221 (position 3) through the winding of relay 226 70 to ground at side switch arm 227 (position 3). Relay 226 closes a locking circuit through to the called line. This circuit may be traced from the ringing source 236 and back contact and outer right-hand armature of relay 225, lower armature and contact of relay 226, brush 233, over the loop of the called line 200 and returning by way of brush 232, contact and upper armature of relay 226, inner right-hand armature and back contact of relay 225 through the right-hand winding of relay 225 to battery and ground. Relay 225 does not energize while ringing current is being applied to the line. 75 80

When the side switch at the connector 240 85 goes into position 3 to prepare for the application of ringing current to the called line, side switch arm 222 includes a resistance 238 in series with the right-hand winding of relay 214 and relay 122 at the outgoing end 90 of the trunk 151, 152. Relay 122 being unable to remain energized in series with the resistance 238, releases its armature and establishes a circuit for driving sequence switch 130 out of position 10 and into position 13. This circuit may be followed from battery through the winding of said sequence switch, contact 139 (10), back contact and armature of relay 122 to ground at contact 140. In position 13, the circuit for the supervisory relay 104 is opened at contact 136. Supervisory relay 104 deenergizes and may in any well-known manner operate a supervisory signal to inform an operator that 95 ringing current is being placed upon the 100 called line. 105

When the called subscriber answers, the resistance of the circuit for the right-hand winding of relay 225 is reduced sufficiently 110 to permit said relay to energize. At its left-hand armature, this relay closes a locking circuit for itself to ground at the off-normal contact 237. At its right-hand armatures, the relay 225 closes the following circuit for the called line relay 224: battery through the left-hand winding of relay 224, front contact and inner right-hand armature of relay 225, upper armature and contact of relay 226, brush 232 over the loop of the called line, brush 233, contact and lower armature of relay 226, outer right-hand armature and front contact of relay 225, right-hand winding of relay 224, left-hand armature and contact of relay 225, to ground at the off-normal contact 237. Talking battery 115 is supplied to the called line through the windings of the relay 224. Relay 224 attracts its armature and shunts out the resist- 120 125

ance 238 so that relay 122 is again permitted to attract its armature. Relay 122 closes a circuit from ground, contact 140, armature and front contact of relay 122, contact 138 65
5 (13) through the winding of sequence switch 130 to battery. Sequence switch 130 thereupon advances into position 14. In position 14 of sequence switch 130, a circuit is established from battery through the 70
10 lower right-hand winding of the repeating coil 103, winding of supervisory relay 104, contact 106, brush 108, terminal 111 through the impedance 146, contact 140 (14) armature and front contact of relay 122, contact 138 (14), contact 137 (14) terminal 110, brush 107, contact 105 through the upper 75
15 right-hand winding of repeating coil 103 to ground. Supervisory relay 104 energizes and in any well-known manner may serve to 80
20 operate a supervisory signal before an operator to indicate that the called subscriber has responded.

At the termination of the conversation, the called subscriber replaces his receiver on the switchhook causing the deenergization 25 of relay 224. Relay 224, by releasing its armature, causes the resistance 238 to again be included in series with the relay 122. Relay 122 therefore deenergizes and opens 30 the circuit for the supervisory relay 104. Relay 104, by deenergizing, may serve to display a signal before the operator indicating that the called subscriber has hung up his receiver. In case of a full automatic 35 system, the relay 104 may operate to initiate the release of the selector switch. In either case, as soon as the power-driven selector switch restores and brush 109 disengages the terminal 112, the relay 121 becomes de- 40 energized. A circuit is now closed including the left-hand armature and back contact of relay 121 and contact 132 to drive sequence switch 130 out of position 14 and into position 1. Sequence switch 130 in passing 45 out of position 14 opens at contacts 141 and 142, the circuit of the calling line relay 214. Relay 214 releases and after an interval, relay 215 deenergizes. Relay 215 at its left- 50 hand armature and back contact closes a circuit including off-normal contact 239 for the release magnet 220. Magnet 220 operates to release the connector switch 240. Relay 215 at its left-hand armature and front contact opens the holding circuit for relay 228 at 55 the selector switch 230. Upon the retraction of the outer right-hand armature of relay 228, a circuit is closed including the armature and back contact of relay 201, inner armature and back contact of relay 202, primary off-normal contact 231 and the winding of release magnet 207. Magnet 207 energizes in this circuit and restores the selector switch 230 to its normal position. The apparatus has now been completely re- 60 turned to normal and may be taken for use 65 in connection with subsequent calls.

Assume that the called line 200 is found to be engaged. In this instance, a ground potential will be found on the multiples of test terminals 235 which ground may be supplied, for example, over a side switch arm 227 of some other connector switch standing in its third position. At the termination of the units series of impulses, relay 216 releases its armature after an interval. The escape magnet 219 however, is maintained energized by means of the following substitute circuit: battery through the winding of said escape magnet, make-before-break contact of relay 216, through 70 the winding of relay 223, normal contact of said relay, side switch arm 227 (position 2), brush 234, and terminal 235 to ground. Relay 223 energizes and locks up in a circuit including its right-hand make-before-break contact and off-normal contact 237. The escape magnet 219 by remaining energized prevents the side switch from advancing into position 3. At the outer right-hand armature of relay 223, a busy tone from the coil B_2 is supplied to the calling line to notify the calling subscriber that the desired line is busy. The calling subscriber by replacing his receiver upon the switchhook either gives a disconnect signal to an operator or automatically causes the release of the switches in the first exchange. The release of the step-by-step switches in the second exchange and of the remaining apparatus takes place as above described. 80

What is claimed is:

1. In a telephone exchange system, a calling line, a called line, a numerically operated switch arranged to be driven in a continuous movement, step-by-step switches, means for operating said first mentioned switch in its continuous movement to extend the calling line, and means for operating said step-by-step switches to further extend the calling line into connection with said called line. 105
2. In a telephone exchange system, a calling line, a called line, a selective switch arranged to be driven in a continuous movement, step-by-step switches, a sender for controlling the operation of said selective switch in its continuous movement to extend the calling line, and means controlled by said sender for operating said step-by-step switches to further extend the calling line into connection with said called line. 110
3. In a telephone exchange system, a calling line, a called line, a selective switch arranged to be driven in a continuous movement, step-by-step switches, a sender for controlling the operation of said selective switch in its continuous movement to extend the calling line, and means arranged to 120
- 125

- operate simultaneously with and under the control of said sender for operating said step-by-step switches to further extend the calling line into connection with said called line.
4. In a telephone exchange system, a calling line, a called line, a selective switch arranged to be driven in a continuous movement, step-by-step switches, a sender for controlling the operation of said selective switch in its continuous movement to extend the calling line, and an auxiliary switch arranged to operate simultaneously with and under the control of said sender for operating said step-by-step switches to further extend the calling line into connection with said called line.
5. In a telephone exchange system, a calling line, a called line, a selective switch arranged to be driven in a continuous movement, a trunk line, step-by-step switches, a sender for controlling the selective operation of said selective switch to extend the calling line to said trunk, and means associated with said trunk and arranged to cooperate with said sender for operating said step-by-step switches to further extend the calling line into connection with said called line.
6. In a telephone exchange system, a calling line, a called line, a selective switch arranged to be driven in a continuous movement, step-by-step switches, a trunk line extending in the direction of said latter switches, a sender for controlling the selective operation of said selective switch to extend the calling line to said trunk, and a sequence switch associated with said trunk and arranged to cooperate with said sender for operating said step-by-step switches to further extend the calling line into connection with said called line.
7. In a telephone exchange system, a calling line, a called line, a selective switch arranged to be driven in a continuous movement, a series of step-by-step switches a sender for controlling the selective operation of said selective switch to extend the calling line, and an auxiliary switch arranged to be driven through a plurality of cycles of operation under the control of said sender for causing the successive operation of said step-by-step switches to further extend the calling line into connection with said called line.
8. In a telephone system, a calling line, a called line, a selective switch arranged to be driven in a continuous movement, step-by-step switches, a trunk line extending in the direction of said step-by-step switches, means for operating said selective switch in its continuous movement to extend the calling line to said trunk, means associated with said trunk for sending impulses thereto, and means responsive to said impulses for operating the step-by-step switches to further extend the calling line into connection with said called line.
9. In a telephone system, a calling line, a called line, a selective switch arranged to be driven in a continuous movement, a trunk line, a step-by-step switch in which said trunk line terminates, a sender, means controlled by said sender for operating said selective switch to extend the calling line to said trunk, means associated with said trunk and under the control of said sender for sending impulses over said trunk, and means responsive to said impulses for operating said step-by-step switch to further extend the calling line in the direction of said called line.
10. In a telephone system, a calling line, a called line, a selective switch arranged to be driven in a continuous movement, a trunk line, a step-by-step switch in which said trunk terminates, a continuously operating source of power for driving said selective switch in its continuous movement to extend the calling line to said trunk, and means for operating said step-by-step switch to further extend the calling line in the direction of said called line.
11. In a telephone system, a line, a selective switch, a second switch arranged to be operated in an interrupted movement, means for operating said selective switch in a continuous uninterrupted movement to its set position to extend said line to the second switch, and means for operating said second switch to further extend said line.
12. In a telephone system, a calling line, a sender, means for transmitting impulses over said line to operate said sender to establish the record of a designation thereon, a step-by-step switch, and means controlled by said sender for sending impulses to operate the step-by-step switch to extend said line in a talking connection.
13. In a telephone exchange system, a calling line, a numerically-operated switch arranged to be driven in a continuous movement, a step-by-step switch, means for operating said first switch in its continuous movement to extend the calling line, and means for operating said step-by-step switch to extend the calling line.
14. In a telephone exchange system, a calling line, a numerically-operated switch arranged to be driven in a continuous movement, a step-by-step switch, means for operating said first-mentioned switch in its continuous movement to extend the calling line, and means for directly operating said step-by-step switch to further extend the calling line.
- In witness whereof, I hereunto subscribe my name this 13th day of August A. D., 1919.

LIPA POLINKOWSKY.
